C. A. SPINDLER

FEED VALVE FOR BOILERS

Filed Oct. 30, 1922

FIG. 1.

FIG. 2.

FIG. 3.

FIG. 4.

Inventor
C. A. Spindler
By William J. Jacobi
Attorney

UNITED STATES PATENT OFFICE.

CLINTON A. SPINDLER, OF MARIETTA, OHIO.

FEED VALVE FOR BOILERS.

Application filed October 30, 1922. Serial No. 597,885.

To all whom it may concern:

Be it known that CLINTON A. SPINDLER, a citizen of the United States, residing at Marietta, in the county of Washington and State of Ohio, has invented certain new and useful Improvements in Feed Valves for Boilers, of which the following is a specification.

My invention relates to boiler feed valves and its principal object is to provide a feed valve wherein the water supply from the boiler may be cut off to obviate freezing of the valve in cold weather.

It is also an object of the invention to provide a feed valve which will permit either side thereof to be used for a blowoff and drain plug and is so constructed as to eliminate an auxiliary blowoff and nipple.

The invention also contemplates a valve which may be constructed and sold at a comparatively small cost and provides a valve and nipple having a blowoff.

These and like objects will be better understood as the description proceeds and as is specifically pointed out in the appended claim.

Referring to the accompanying drawing which forms a part of this specification,

Figure 1 is a vertical sectional view of a blowoff valve constructed in accordance with my invention.

Figure 2 is a horizontal sectional view taken on lines 2—2 of Fig. 1.

Figure 3 is an elevation of the valve associated with a boiler, and

Figure 4 is a horizontal sectional view taken on lines 4—4 of Fig. 1.

Referring to the drawing in detail wherein like characters of reference denote like parts throughout the several views, the numeral 5 designates the valve casing or barrel having laterally extending nipples 6 at diametrically opposite points. One of these nipples is adapted to be connected to the boiler feed water supply while the other constitutes the blowoff. The lower end of the valve casing or barrel is provided with an exterior screw thread 7 which is threaded to the boiler while the upper end is provided with a packing gland 8 in which a valve stem 9

extends the latter passing longitudinally through the barrel or casing 5.

Supported within the valve casing or barrel 5 at the upper end thereof is a spider 9 to which an internally threaded sleeve 10 is secured and which threadedly receives the valve stem 9. A similar spider 11 is arranged in the valve casing or barrel 5 adjacent the lower end thereof and is provided with a central guide 12 through which the valve stem 9 passes.

A conical valve element 13 is carried by the lower end of the valve stem 9 and is adapted to seat on a seat 14 formed in the lower end of the valve casing or barrel 5.

From the disclosure it will be obvious that I have provided a simple and inexpensive blowoff valve either nipple of which may be used as a blowoff or connected with the feed water supply. Also my improved valve will eliminate freezing during cold weather by operating the valve to seat on the seat 14.

While I have shown and described the preferred form of my invention, I realize that various minor changes may be resorted to, without departing from the spirit and scope of the invention as claimed, therefore, I do not wish to limit myself to the exact details of construction shown, nor to the combination and arrangement of parts.

What I claim as new and desire to secure by Letters Patent is:—

In combination with a boiler, a valve barrel provided with a valve seat at one end, a plug threaded in the upper end of the barrel, a packing clamp fitted thereon, spiders arranged within the barrel, one of said spiders having an internally threaded sleeve, a threaded stem passing through the plug, the threaded sleeve and the said spiders, a valve carried by the lower end of the stem and engageable with the valve seat, and laterally disposed nipples on the barrel positioned at substantially right angles to the barrel and adapted to be connected to the boiler feed water supply, forming a cutoff means to prevent freezing in cold weather, substantially as described.

In testimony whereof I affix my signature.

CLINTON A. SPINDLER.
